UNITED STATES PATENT OFFICE

HENRY CLAY BABEL, OF BUFFALO, NEW YORK.

HANDLE FOR AUTOMOBILE BATTERY BOXES.

Application filed February 16, 1922. Serial No. 537,097.

To all whom it may concern:

Be it known that I, HENRY CLAY BABEL, a citizen of the United States, residing at Buffalo, in the county of Erie and State 5 of New York, have invented new and useful Improvements in Handles for Automobile Battery Boxes, of which the following is a specification.

The invention relates to a handle for 10 automobile battery boxes.

Heretofore battery boxes have been equipped with U-shaped handles having shanks secured in the material of the battery boxes but it has been necessary to bore 15 through the wood of the battery box and counter-bore the same for the reception of anchoring or securing means for fastening the shank portions in the material and this has necessitated covering or embedding the 20 anchoring or securing means in asphaltum or similar substance, which in spite of the supposed acid resisting qualities permits the acid to penetrate to the securing means of the handles with the fatal result of 25 grooving the wood and causing the handles to break or pull out.

The object of the present invention is to prolong the life of battery boxes and to provide a simple, practical and efficient battery 30 box handle of strong, durable and comparatively inexpensive construction, which may be easily applied to a battery box and which will not require the application of such acid resisting material to the battery box for 35 covering or protecting the wood and the fastening means of the handle.

Another object of the invention is to provide a battery box handle adapted to be constructed of a single piece of wire or 40 similar material and capable of being readily introduced into the bores or openings of the battery box and securely locked within the same without employing nuts or similar fastening means.

With these and other objects in view the invention consists in the construction and novel combination and arrangement of parts hereinafter fully described, illustrated in the accompanying drawings and pointed 45 out in the claims hereto appended, it being understood that various changes in the form, proportion and minor details of construction, within the scope of the claims, may be resorted to without departing from 50 the spirit or sacrificing any of the advantages of the invention.

In the drawings, in which like characters of reference designate corresponding parts in the several views:—

Figure 1 is an elevation of a battery box 60 handle constructed in accordance with this invention and showing the same preparatory to applying the handle to the battery box, the latter being in section to illustrate the downwardly diverging bores or openings 65 for the shanks of the handle.

Figure 2 is a similar view showing the handle applied and locked in position in the bores or openings of the battery box.

In the accompanying drawing in which 70 is illustrated the preferred embodiment of the invention, 1 designates a battery box handle designed to be constructed of stout wire or other suitable material and comprising downwardly diverging shanks 2, 75 side portions 3 and a connecting grip portion 4. The downwardly diverging shanks or prongs 2, which are preferably arranged at an angle of 45 degrees are arranged in downwardly diverging bores or openings 5 80 extending downwardly from the upper edge 6 of the portion 7 of the battery box and terminating short of the lower edge 8 of the same so that the bores or openings 2 do not extend entirely through the portion 7 85 of the battery box. In order to enable the downwardly diverging shanks or prongs of the handle to be readily introduced into the openings or bores 5 of the battery box the side portions 3 of the handle are bowed or 90 bent inwardly, as clearly illustrated in Figure 1 of the drawing, the bowing or bending being preferably of angular formation, as shown and the grip portion is preferably bowed outwardly, as illustrated in Figure 95 1 to cooperate with the inwardly bowed side portions 3 for enabling the side shanks or prongs to be inserted in the bores or openings 2 of the battery box. The shanks or prongs 2 are preferably forced into openings 5, the walls of which are tightly engaged by the shanks or prongs and as the said shanks or prongs are forced into the openings 5 the side portions 3 of the handle and also the grip portion thereof, are 100 straightened and finally brought to the position illustrated in Figure 2 of the drawing, in which the grip portion is horizontal and the exterior side portions are arranged vertically. This straightening of the 105 bowed side and grip portions of the handle not only facilitates the introduction of the 110

divergent shanks or prongs into the material of the battery box but it also serves to lock the shanks or prongs into openings of the battery box so that the handles are able 5 to sustain the weight of the storage batteries of automobiles without liability of the handles bending or pulling out and it will be apparent that it will be impossible for the downwardly divergent shanks or 10 prongs of the handle to pull out while the side portions and the grip portions are arranged vertically and horizontally, as shown in Figure 2. The shanks or prongs may be roughened or provided with spurs to assist 15 in firmly and securely fastening the shanks or prongs in the openings of the battery box.

It will be clear that by locking the downwardly diverging prongs in the correspondingly disposed openings that it obviates the 20 necessity of boring entirely through the material of the battery box and it also dispenses with nuts and similar fastening means so that it is not necessary to counter-bore the 25 material of the battery box and seal such perforations or cover such fastening means in the counter-bores by coating or covering same with asphaltum or similar material, as the acid will be unable to penetrate the material 30 of the battery box and cannot attack the shanks of the handle, whereby the life of the battery boxes will be materially prolonged. Also it will be clear that by constructing the handles of a single piece of 35 wire or similar material in the form shown, that the handles for battery boxes will be materially cheapened and that the handles may be applied more quickly and with greater ease than heretofore. While the handles are 40 particularly adapted for battery boxes yet it will be clear that they may also be employed for various other purposes.

What is claimed is:

1. A handle of the character described, 45 constructed of a single piece of material and comprising downwardly diverging prongs designed to be embedded in the material of a battery box, inwardly directed side portions arranged exteriorly of the material of

the battery box and a bent grip portion connecting the side portions of the handle, said bent grip portions of the handle being adapted to be straightened to spread the side portions and permit the shanks to be introduced into position and to cause the said shanks to 55 be locked in such position.

2. A handle of the character described, constructed of a single piece of material and comprising downwardly diverging shanks designed to be embedded in the material of 60 a battery box, inwardly directed side portions extending from the shanks and arranged exteriorly of the battery box, and a bent grip portion connecting the side portions, said bent grip and also said side portions being adapted to be manipulated to permit the downwardly diverging shanks to be placed in position and to be locked in position.

3. A handle of the character described, 70 constructed of a single piece of material and including a downwardly diverging shank designed to be connected with a battery box, inwardly converging side portions connected with the shanks, and an upwardly bent grip 75 portion connecting the side portions, said bent grip portion being adapted to be straightened to separate the inner ends of the side portions apart into substantial parallelism and thereby to permit the shanks 80 to be positioned for a locking connection with the box.

4. A combination with a battery box, having downwardly diverging sockets closed at their lower ends, of a handle constructed of a 85 single piece of material and comprising downwardly diverging shanks, inwardly directed side portions connected with the prongs and an upwardly bowed grip portion connecting the side portions, said bowed grip portion adapted to be straightened to spread the side portions and permit the shanks to be introduced into the sockets of the battery box and be locked therein.

In testimony whereof I have hereunto set 95 my hand.

HENRY CLAY BABEL.
